BRAKE APPARATUS FOR OIL WELL PULLING EQUIPMENT

Russell Brinneeman, Bartlesville, Okla., assignor
to Phillips Petroleum Company, a corporation
of Delaware

Application April 27, 1939, Serial No. 270,468

2 Claims. (Cl. 188—99)

The present invention relates to brake apparatus to be placed on pulling units used in pulling a bailer, casing, tubings, rods, etc., from a well hole and also for use in running a bailer, casing, tubing, rods, etc., into a well bore.

At the present time, bailers, rods, and tubing are pulled and run into the well by winches and lifting hoists, which winches and lifting hoists are generally mounted on truck units and can be moved from well to well as needed. The mobile truck pulling units usually have some engine power means of some type, a cable drum on which the pulling cable is mounted and some type of brake mechanism to stop the tubing, rods or bailer being pulled or lowered into the well. The cable goes over the crown block in the derrick with the end being attached by suitable coupling means to the bailer, tubing or rods to be pulled or lowered into the well. The pulling unit, of which there are a number on the market, and as an example where the present unit may be used, the "Cardwell" unit is mentioned. The pulling unit pulls up to the well and the cable wound on the drum is run over the crown block on top of the derrick. The free end of the cable has suitable coupling members to attach to the bailer, tubing or rods being pulled from the well. The engine of the pulling unit is started in operation and after the coupling has been made to the tubing, bailer or rods to be pulled, a clutch is actuated on the pulling unit which transmits the power from the engine to the cable drum, thus rotating the drum which in turn winds the cable thereon and lifts the bailer, tubing or rods from the well. The brake mechanism finds very little application in the lifting operation. Most of the braking is done by closing down the engine or by the clutch and by chucks on the derrick floor.

When it comes time to run tubing or rods into the well and particularly a bailer when bailing of a well is necessary, the brake mechanism is a very important item in the pulling unit. With tubing or rods, the respective sections must be coupled together and the lowering proceeds very slowly, and the brake mechanism is used mostly to hold the rod line or tubing or to regulate the rate at which it descends into the hole. The engine is not used, the clutch being disengaged, and the weight of the tubing or rods falling by gravity is depended upon to lower the string and the brake merely regulates the rate of descent and stops the descent after which chucks are used to hold the string until the next length of tubing or rods is coupled to the string. With

5 a bailer, the operation is somewhat different since it is necessary to send the bailer to the bottom of the hole. In wells 10,000 feet deep, in order to conserve time, it is necessary to get the bailer to the bottom of the well as quickly as possible. The usual practice is to allow the bailer to fall by gravity within the hole and start stopping the bailer within the last 200 feet of travel. This is done by disengaging the clutch from the engine and just allowing the cable drum to rotate.

10 At the present time, friction brakes are employed on the cable drums. The brakes are of the usual brake shoe and lining type and by actuating the brake shoe, the lining is placed in frictional contact with a rotating shaft which tends to stop the motion of the drum. The drums at present attain high rotative speeds which place quite a burden on the brake linings of the brake shoes. Instances have occurred where the brake linings have caught on fire, thus disintegrating the lining resulting in failure of the brakes. Serious accidents have occurred where the falling bailer has gained so much speed that the drum from which the cable is unwinding is unable to withstand the terrific speed and has flown off into space due to the failure of the friction brakes to function when needed. The brakes are necessarily large, which requires large brake linings. To reline and re-service brakes is a very expensive operation and one to be avoided if possible.

15 It is an object of the present invention to provide a hydraulic braking means for the pulling unit used in well service operations.

20 It is a further object of the present invention to provide braking apparatus for well servicing units which is positive in operation, more economical in operation, creates less shock and impacts on the equipment when applied and possessed of safety means to prevent mis-application by an inexperienced operator.

25 It is still a further object of this invention to provide braking apparatus for well servicing units which is more durable than present day equipment and less costly to keep in repair.

30 Other objects and advantages of the invention will be apparent during the course of the following description.

35 In the accompanying drawings, forming a part of this specification, and in which like numerals are employed to designate like parts throughout the same:

40 Figure 1 is a diagrammatic view of a well der-

rick with the pulling unit mounted alongside the derrick.

Figure 2 is a vertical sectional view of one-half the brake mechanism and a plan view of the other half.

Figure 3 is a sectional view taken on the line 3—3 of Figure 2, and

Figure 4 is a plan view of the top of the brake mechanism which is the manifold.

In the drawings, wherein for the purposes of illustration, is shown a preferred embodiment of my invention, the numeral 10 represents the derrick for the oil well 11. The crown block 12 on top of the derrick has the cable 13 passing therewith one end being attached to a member going into the well bore 11 and the other end attached to the drum 14 on the support 15. The support 15 may be stationary or may be the body of a truck so that the lifting mechanism may be portable. An engine 16' which may be of any design, is mounted on the support 15 and connects through sprocket chain 16 to the gear 17 mounted on one end of the shaft 18 extending outwardly from the drum 14. A clutch 19 is mounted between the gear 17 and drum 14 so as to disengage the engine from the rotatable drum. The opposite end of the shaft 18 has the gear 20 thereon which connects by sprocket chain 21 to the brake mechanism 22.

In operation the cable 13 is unwound from the drum 14, passed over crown block 12, brought down to the derrick floor where it is attached to either rods, tubing or a bailer by any known coupling means. If the tubing, rods or bailer is to be lifted, the engine 16 is set in operation which in turn, through sprocket chain 16 rotates gear 17. The clutch 19 is then placed in engagement with gear 17 through shaft 18 and the drum 14 thus rotates winding the cable 13 thereon. During this time the brake 22 is fully open which allows the drum to rotate freely. To stop the winding of the cable on the drum, the engine can be slowed down to stop the drum, or the clutch 19 can be disengaged and the brake 22 set which will prevent the drum 14 from revolving in the reverse direction and allowing whatever is being raised from falling back into the well hole. In lowering into the well hole, the engine is not used, hence the clutch 19 is disengaged and the weight of the article being lowered is allowed to fall by the force of gravity into the hole, which in turn pulls the cable off the drum and rotates the same. To prevent the drum 14 from rotating at excessive speeds due to the falling article accelerating in the well hole, the brake 22 may be set to regulate the speed of descent or may be applied intermittently to slacken the speed of the falling object. The brake 22 is set in closed position when a complete stop is desired which in turn stops rotation of the drum 14 and prevents any more cable 13 from going into the hole.

The brake 22 is a hydraulic braking mechanism comprising a housing member 23 having end portions 24 and 25 to receive the ends 26 and 27 of crank shaft member 28. The end of the crank shaft 26 has a coupling member 29 thereon to connect directly into the shaft from the drum 14 or through a sprocket chain 21 into the drum 14. The housing 23 has support members 30 and 31 which present bearing surfaces 32 and 33 for the crank shaft passing therethrough. The ends 26 and 27 of the crank shaft are mounted in suitable bearings 34 and 35 in the end portions 24 and 25. The housing 23 has six

cylinders therein with cylinders 36 and 36', 37 and 37', and 38 and 38' being in the same straight line and directly opposite each other. The ends of each cylinder are closed by cover plates 39. 5 Mounted to reciprocate in each cylinder are the pistons 40 and 40' in the cylinders 36 and 36', pistons 41 and 41' in the cylinders 37 and 37', and pistons 42 and 42' in the cylinders 38 and 38'. The pistons 40 and 40' are connected to the crank shaft 28 at 43 through suitable bearings 44. The pistons 41 and 41' and 42 and 42' are connected to the crank shaft 28 at 45 and 46 respectively through suitable bearing members. The space or sump 47 is filled with oil as are the cylinders.

Figures 3 and 4 show the manifold cover 48 having therein the conduits 49, 50 and 51 which conduits connect with the ends of the cylinders 36 and 36', 37 and 37', and 38 and 38' as more clearly shown in Figure 3 by means of passages 52 leading out from the end of each cylinder. Each passage 49, 50 and 51 has the valve member 53 passing therethrough which valve is actuated by the handle or control 54. The valve member 53 has openings 55, 56 and 57 therein and when the valve member 53 is turned as shown in Figure 3, the passage 50 is open to flow with no restriction. If handle 54 is turned, the passage 56 will move out of the position shown in Figure 3 and offer a restriction to flow and continued turning will completely close off the passage.

Each piston member has a passage 58 bored longitudinally of the piston connecting with the chamber 59 formed in the end of the piston. The chamber 59 is closed by check valve 60 which is held closed by coil spring 61. Each cylinder has a passage 62 in the housing 23 connecting the cylinder with the sump 47. The passage 62 is closed during the greater portion of the piston's movement but is opened for a short period of time when the piston reaches its extreme rearward position. This allows oil from the sump to flow into the cylinder and replace any oil which may have leaked out of the cylinder.

45 In operation, the brake is connected into an organization such as shown in Figure 1. The coupling means 29 on the brake is either connected directly to the shaft of the cable drum or is connected by means of the sprocket chain 21 as shown in Figure 1. By this means, as the shaft 18 of the drum 14 rotates, its rotation will be transmitted to the brake mechanism and crank shaft 28 will rotate at the same speed as the cable drum 14.

55 As previously stated the cylinders and sump 47 are filled with an oil of about 10W viscosity. With the crank shaft 28 being rotated, pistons 40 and 40', 41 and 41', and 42 and 42' will reciprocate back and forth forcing the oil through passages 52 into conduits 49, 50 and 51 in the manifold into the cylinder on the opposite side as they reciprocate back and forth. As long as the valve 53 is fully open, the oil or fluid will pass back and forth from the cylinders opposite each other and offer no resistance to the rate at which the pistons reciprocate. If the valve 53 is closed slightly by actuating handle 54, that is, have the passages 55, 56 and 57 slightly restricted, the oil or fluid will not pass as freely from cylinders on opposite sides of each other since the liquid medium is non-compressible. This slows down the speed of the crank shaft 28 which crank shaft, being connected directly to the cable drum, tends to slow down the speed of the drum. If the valve 53 is completely closed,

no oil will pass from cylinder to cylinder, hence the pistons cannot reciprocate and the crank shaft cannot rotate. This in turn is transmitted to the cable drum and stops rotation of the same.

The oil in the sump 41 and cylinders also lubricates the pistons in the cylinders and the bearings of the crank shaft. If any oil leaks out of the cylinders, the piston in its rearward movement creates a vacuum so that when it leaves the position in the cylinder where it uncovers passage 62, oil from the sump will rush into the cylinder to insure that the cylinders are always full of oil. Very little oil is lost in operation and it does not become necessary often to fill the sump but suitable openings may be provided to the sump for filling purposes.

The check valve 60 is placed in the end of each piston as a precaution against damage to equipment from the sudden closing of the valve 53. The spring 61 is so tensioned as to open when a pressure develops in the oil flow lines which exceeds the tensile strength of any of the equipment in the lifting unit. If the operator of the brake should suddenly close the valve when a bailer was travelling at an accelerated speed in the well, tremendous pressures would build up immediately from the piston's being stopped almost immediately. This would be accompanied by terrific impact stresses throughout the whole equipment and would result in the weakest member of the organization giving way. The spring 61 is tensioned usually at the known tensile strength of the sprocket chains which are generally the weakest members in the organization. When excessive pressures develop, spring 61 will be compressed, opening valve 60 and oil flow will pass through passage 53 into the sump, thus relieving the extreme pressure conditions. As previously explained when the extreme conditions pass, the cylinders will again be filled from passage 62.

If the brake receives any sustained use over a long period there is a possibility that the lubricating oil may carbonize from excessive heating of the oil. If the use of the brake is such that the oil may be subjected to excessive heat, then suitable cooling means may be provided and is within the scope of the present invention.

It is to be understood that the form of my in-

vention, herewith shown and described, is to be taken as a preferred example of the same, and that various changes in shape, size and arrangement of parts may be resorted to without departing from the spirit of my invention, or the scope of the subjoined claims.

Having thus described my invention, I claim:

1. A braking system for use with oil well pulling equipment comprising a drum; a tool suspending cable wound on the drum; a hydraulic brake including a housing, a crank shaft rotatable in the housing and having one end extending therethrough, a pair of oppositely arranged cylinders within the housing, a piston reciprocable in each cylinder and connected to the crank shaft, a passage for transmitting a liquid medium into the outer end of both cylinders, a valve for controlling the flow of liquid medium through the passage, a chamber within the housing, means responsive to fluid pressure in each cylinder for placing the chamber in communication with the passage, and means for placing the chamber in communication with the outer end of each cylinder upon a predetermined movement of each piston within its cylinder; and means adapted for connecting one end of the crank shaft to the drum.

2. A braking system for use with oil well pulling equipment comprising a drum, a tool suspending cable wound on the drum, a housing member, a crank shaft rotatable in the housing, means adapted for connecting one end of the crank shaft to the drum, pairs of oppositely arranged cylinders in the housing, a piston reciprocable in each cylinder and connected to the crank shaft, a manifold member, a chamber formed by the housing member and the manifold member, a passage in the manifold member connecting the outer ends of the pairs of oppositely arranged cylinders, a liquid medium substantially filling the cylinders, the chamber and the passage in the manifold member, means responsive to fluid pressure in each cylinder for placing the chamber in communication with the passage, and means for placing the chamber in communication with the outer end of each cylinder upon a predetermined movement of the corresponding piston.

RUSSELL BRINNEMAN.
